UNITED STATES PATENT OFFICE.

ORREL A. PARKER, OF CLEVELAND, OHIO.

HUB STRUCTURE FOR METAL WHEELS.

Application filed May 18, 1921. Serial No. 470,541.

This invention relates generally to metallic wheels and more particularly to a novel construction of hub structure, the object being to provide a strong and simple wheel comprising tubular spokes together with the necessary means for spacing and bracing the same and whereby there is provided an exceedingly light wheel which will possess all the necessary strength to withstand lateral torsional and radial strains.

Another object of the invention is to provide a metal wheel embodying these characteristic features which can be manufactured at a minimum cost.

With these various objects in view the invention consists in the novel features of construction, and in the manner of combining or arranging the same, all of which will be fully described hereinafter and pointed out in the appended claims.

In the drawings forming a part of the specification, Fig. 1 is a side elevation partly in section of one construction of a wheel embodying my invention; Fig. 2 is a similar view showing the spokes formed with flattened inner portions; Fig. 3 is a similar view showing a slight modification of the construction shown in Fig. 2; Fig. 4 is a similar view showing a still further modification; Fig. 5 is a vertical sectional view on the line 5—5 of Fig. 3; Fig. 6 is a detail perspective view of one of the gussets employed to connect the inner portions of two adjacent spokes; Fig. 7 is a vertical sectional view of one of said gussets; Figs. 8 and 9 show sectional views of modified details of construction; and Figs. 10 and 11 are modified forms of gussets.

In carrying out my invention I employ a plurality of sheet metal tubular spokes 10, it being understood that any desired number of spokes may be employed, and in the drawings I have illustrated a wheel comprising ten spokes, four of which are slightly shorter than the other six, these four being provided at their outer end with clamps 11, carried by bolts 12 working in nuts 13 arranged in sockets 14 fixed in the ends of the four short spokes, each clamp fulcruming upon the shoulder or offset 15 formed upon the outer face of the tubular spoke adjacent the end thereof.

Two of the spokes, preferably those disposed directly opposite the central clamp carrying spokes, are connected by means of

a plate 17, said plate being connected to the spoke ends by welding or any other suitable manner and closing the ends thereof and the ends of the other spokes, which are not provided with clamps, are closed by 60 means of plates or caps 16, if desired.

The plate 17 may be provided with a valve stem opening 18 and also openings 19, to receive the driving lugs 20 carried by the demountable tire carrying rim 21.

In the construction shown in Figs. 1, 2, and 3 the plate is provided with a valve stem opening 18 inasmuch as the valve stem opening 22 in the rim is arranged adjacent to the diagonal split 23, but in the construction shown in Fig. 4 the valve stem opening 22 is placed some distance to one side of the straight split 24 made in the rim, and in this construction it will not be necessary to have a central valve stem opening 18 in the plate.

The inner portions of the spokes 10 are connected by means of thin sheet metal gussets 28 in order to rigidly connect all of the spokes together, each gusset comprising a central or bridging portion 29 and the parallel tapered wing portions 30, and in practice I prefer to make the central or bridging portion curved as shown and with curved ends 31 so as to fit snugly into contact with the curved exteriors of the spokes 85 and provide substantially unbroken unions between the spokes and gussets.

The edges of the flat wing portions 30 will contact with the sides of the spokes, the edges 32 of each adjacent pair of gussets approaching each other as most clearly shown and then by means of a welding torch or electrode I can quickly and easily weld the adjacent edges of the gussets to each other and to the spokes, and if desired, can solder, 95 weld or braze along the lines 33 where the curved ends 31 of the gusset contact with the spoke.

By means of these thin sheet metal gussets thus arranged between the inner portions of the spokes and welded thereto I am able to provide an exceedingly cheap, simple and durable wheel body ready to receive the hub therein and to have the hub flanges applied thereto. If desired, the inner edges of the 100 gusset may be turned inwardly as indicated at 33^a and brought into contact with the inner portions of the spoke ends to prevent bulging or buckling of said spoke ends.

The inner portions of the spokes 10 may 110

be flattened substantially into the form of a rectangle as indicated at 26 with transition portions 27 between the round and flattened portions of the spoke, and the maximum diameter of this rectangular portion of the spoke is preferably the same as the maximum diameter of the tubular portion of the spoke, and I am therefore able to obtain the full strength of the spoke at the inner end to withstand the lateral strains placed thereon, it being well known that the greatest strains are placed upon the spokes adjacent the inner ends thereof.

The spokes having the flattened inner portions are connected by means of gussets 28 exactly in the manner already described, the edges 32 being welded to the flattened portions of the spoke while the curved edges 31 are secured to the curved portions of the spoke just beyond the transition portions 27.

A wheel body composed of tubular metal spokes having their inner portions flattened and connected together by means of the thin metal gussets will be light and at the same time strong and durable inasmuch as I have the full strength of the tube at the inner end to withstand lateral strains and provide rigid braces between the spoke ends in the form of the gussets for the purpose of resisting circumferential strains to which the spokes are subjected.

In the construction shown in Figs. 1 and 2 the gussets extend to the extreme inner ends of the spokes but in the construction shown in Fig. 3 I employ a gusset 35 which is somewhat shorter than the gusset 28 but is connected to the spoke ends in exactly the same manner and in addition to the gussets 35 I employ thin sheet metal spacing rings 36 of the same thickness as the gussets and which are applied to the opposite sides of the spokes and preferably welded thereto. It will be noted that in the construction of wheel shown in Fig. 3 the flattened ends of the spokes are brought into contact with one another whereas in the construction shown in Fig. 2 they are spaced slightly apart. In the construction shown in Fig. 4 I employ a gusset 35 and in connection therewith use sheet metal spacing rings 38 which are also of less radial dimension than the rings 36 and in this structure illustrated in Fig. 4 the flattened ends of the spokes are also arranged slightly apart and between the ends thus spaced I arrange brace pieces 39 which are welded to the spoke ends before the rings are applied.

It is obvious that in case the hub flange bolts are passed through the spokes, it will be necessary to bore the tubular spokes centrally and in a six bolt hub I bore two spokes for the passage of the hub bolts and the remainder of the bolts will pass either through the gussets or through the space between the gussets and rings. In case a five bolt hub is

used in a ten spoke wheel, a bolt will pass through each alternate spoke.

The rings are employed to fill up the space and provide proper bearing surfaces for the hub flanges and if desired the hub flanges 40 can be machined to receive the gussets as most clearly shown in Fig. 8 and in this event the spacing rings 35 and 36 can be dispensed with, and they can also be dispensed with when the spokes are sufficiently flattened at their extreme inner ends so that their greatest width is the same as the adjacent portion plus the thickness of the gusset as shown in Fig. 9 and they can also be dispensed with when the spoke ends are sufficiently widened to fill up the space.

The connecting plate 17 is of a width co-extensive with the width of the spoke ends and consequently I am able to apply the demountable tire carrying rim to the wheel body with very little clearance owing to the fact that the broad felly band usually employed is dispensed with, and consequently the buttoning on of the rim can be accomplished with a very small clearance between the rim and the ends of the spokes carrying the clamps.

When the demountable tire carrying rim is made with a diagonal split the valve stem hole is preferably placed as close as possible to the split so that the valve stem spreader can bridge the same, and in this case the valve stem will be projected through the central opening in the bridge plate, whereas when a straight split rim is provided the valve stem hole will be spaced some distance from the split and in placing the rim upon the wheel, the valve stem can be arranged between two of the unconnected spokes as most clearly shown in Fig. 4.

The clamping levers or toggles employed in connection with this improved construction of metal wheel are substantially the same as those shown and described in the Gibson Patent No. 986,452 and in Patents Nos. 1,188,353 and 1,294,825 granted to me.

It will thus be seen that I provide an exceedingly simple construction of sheet metal wheel, one which will be exceedingly light and at the same time possess great strength and durability, one which will lend itself to the quick and easy mounting and demounting of a tire carrying rim thereon properly positioned and tensioned, and one which can be used in connection with the ordinary type of hubs employed in wooden wheels.

Having thus described my invention, what I claim is:

1. A wheel comprising a plurality of tubular spokes, the inner portions of which are flattened transverse to the plane of the wheel body, and gussets interposed between the inner portions of said spokes, said gussets comprising each an arcuate portion and

parallel wing portions, said wing portions being connected to the sides of the flattened portions of said spokes, and the ends of the arcuate portion connected to the round portion of said spokes.

2. A wheel comprising a plurality of tubular spokes, gussets interposed between the inner portions of said spokes and connected thereto, and spacing rings arranged 10 within the gussets.

3. A wheel comprising a plurality of tubular spokes, gussets interposed between the inner portions of said spokes and connected thereto, brace members connecting the inner portions of said spokes and spacing rings arranged upon the opposite sides of said spokes within the gussets. 15

4. A wheel comprising a plurality of

tubular spokes having their inner portions flattened, gussets interposed between the inner portions of said spokes and connected thereto, and spacing rings arranged within said gussets and connected to the sides of the flattened portions of the spokes.

5. A wheel comprising a plurality of 25 tubular spokes the inner portions of which are flattened, gussets interposed between the inner portions of said spokes and connected thereto, brace members connecting the inner portions of said spokes and spacing rings 30 arranged upon opposite sides of the flattened portions of said spokes and connected thereto.

In testimony whereof, I hereunto affix my signature.

ORREL A. PARKER.
